Application March 31, 1933, Serial No. 663,842
In Great Britain April 4, 1932

16 Claims. (Cl. 179—18)

This invention relates to automatic telephone systems and is more particularly concerned with the routing of calls in multi-exchange areas.

In such areas outgoing traffic from an exchange may proceed over direct junctions to the required exchange or may have to be routed over a tandem exchange.

In areas in which subscriber numbers consist of an exchange code followed by a line number it is usual to register the code and numerical digits in a register translator and to transmit the translated code and the untranslated numerical digits from the register translator to set code and numerical selectors. All calls are dealt with by register translators and the numerical digits are registered. This method of working is not the most economical and especially in systems in which direct inter-exchange junctions are generally available.

One variation of the method of working mentioned which avoids the storing of numerical digits, except where a tandem exchange is in question, is described in British patent specification No. 220,364 in which the exchange code is used in a by-path route to select a junction in a required direction.

It has also been proposed in multi-exchange areas to route a call which would normally proceed over a direct junction, over an intermediate exchange or exchanges if the direct junctions are all engaged. In this case it may well be economical to provide a lesser number of direct junctions which are consequently more frequently occupied and send part of the traffic over the tandem route.

To some extent the routing arrangements of the present invention are based upon considerations of junction occupation. If a group of outlets is straight multiplied over a number of selecting switches, the earlier choices work substantially at maximum capacity, in intermediate choices utilization falls off rapidly and last choices are little used.

By the arrangements of the present invention a saving in apparatus is effected, this saving resulting from the fact that all switches for outgoing groups (i. e. both first selectors and auxiliary selectors) are efficiently used, since they are, in general, used for carrying traffic for all or a considerable number of groups. A further saving of apparatus results from the fact that numerical storage and machine impulsing are obviated in the case of a call routed over a direct outlet of a first selector.

According to the present invention, in a multi-office automatic telephone system, an exchange

is connected to a number of other exchanges by direct junctions and a routing system is provided wherein, at such an exchange, first selectors have, in general, access to a part of each group, or to a part of some groups, of direct junctions to other exchanges, and are provided with a common group of overflow outlets over which access is had to auxiliary selectors in the banks of which appear further and different junctions of the groups.

One of the groups of direct junctions referred to above as those by which an exchange may be connected to other exchanges may be the links leading to local numerical selectors situated at the exchange under consideration and being those over which local connections are set up and it may be that one of the groups of further and different junctions is so connected.

The auxiliary selectors have in general access to the same other exchanges, such access being had over the further and different junctions which represent later choice junctions, and to other junction outlets leading to tandem exchanges through which calls are passed either because they normally pass therethrough, that is there are no direct junctions, or because the tandem exchanges provide alternative routes for calls which normally pass over the direct junctions or, failing an idle such, over the further and different junctions.

Junctions or links to a manual board preferably though not necessarily, appear in the first selectors.

The junction multiple of the first selectors may be common to all first selectors in the exchange or may be divided to give access to separate groups of "early choices" as may be best. Similarly there may be only one group of auxiliary selectors or more than one group.

The auxiliary group of selectors has available to it apparatus for sending out tandem trains and for storing and repeating numerical impulses. The information as to the group of outlets required in an auxiliary selector is conveyed to the control apparatus of the auxiliary selectors from the like operators of the first selectors, for instance by means of a train or trains of impulses sent forward over one speaking wire.

It may be that the junctions to tandem exchanges appear in the banks of the first, instead of in those of the auxiliary selectors in which case apparatus similar to that available to the auxiliary group of selectors may then be associated with the junctions. As this apparatus, which would have to store and to repeat numerical digits and to send tandem trains, may be similar to that

available to the auxiliary group of selectors, it has not been thought necessary to describe it herein. The necessary modifications could be made by those skilled in the art and to whom this specification is directed.

The selectors may be of the rotary one motion type and may be steered to the required group of outlets by a marking or markings applied from the control apparatus.

16 First selectors may be permanently associated with call finders and tandem call finders may be employed.

15 The feeding bridges used in a talking connection can be situated at a first selector or at the outgoing end of a junction in all cases or, alternatively, at the outgoing end of junctions as regards first selectors or at the auxiliary selector if one is called in. As these matters do not form part of the invention they will not be further referred to herein.

25 The term "tandem exchange" or "tandem centre" used herein is not to be understood as being applied to an exchange or centre serving exclusively as a tandem exchange or centre. It may be that the exchange or centre serves in that capacity only incidentally. Moreover, it may be possible to route a tandem connection preferably to one tandem exchange and, if no outlet thereto is idle, secondarily to another exchange, and so on. The manner of effecting this will be apparent from a study of the following description and such an arrangement is to be understood to be within the terms of the claims, the word tandem centre or tandem exchange being understood to 35 include the plural form.

The invention will now be described with reference to Figs. 1-5 of the accompanying drawings in which it is illustrated by way of example.

40 Of the figures, Figs. 1A, 1B, 2A and 2B illustrate a first junction selector which may be referred to as FJS, and common controlling apparatus by which, in common with other selectors FJS, it is served. The first junction selector and its individual apparatus is shown in the upper part of Fig. 1 and the common control apparatus, which may be referred to as FCC, in the lower part of Fig. 1 and in Fig. 2.

50 Figs. 3A, 3B, 4, 5A and 5B illustrate a second junction selector, which may be referred to as SJL, and common controlling apparatus by which, in common with other selectors SJL, it is served. The second junction selector and its individual apparatus is shown in the upper part of Fig. 3 and the common apparatus, which may be referred to as SCC in the lower part of Fig. 3 and in Figs. 4 and 5.

55 The selectors FJS and SJL, as well as switch FMS in FCC and MA in SCC are represented diagrammatically as of the type described in British patent specification No. 388,173. In the common controlling apparatus, in addition to switches FMA and MA respectively, which are marking switches, there are a number of switches as AS, BS, CS in FCC, and ASA, BSA, CSA, MS, HS, TS and US in SCC which act as registers to register the several trains of impulses as they are received. Of these switches AS, BS and CS register the ABC code in response to impulses delivered from the calling line switches. ASA, BSA, CSA register this code, if the connection has to be routed over switch SJL in response to impulses delivered from the FCC switches, and switches MS, HS, TS and US register the numerical part of the called number if the connection has to be routed over switch SJL. Impulses for setting switches HS, TS and

US are delivered to these switches directly from the calling line. As, however, apparatus SCC may not be ready to receive the thousands digit, that is the digit which should be registered on switch MS, by the time the caller is ready to send in that digit, it is arranged that the thousands digit shall be received on switch AS in FCC and transferred to MS in SCC after the ABC code digits have been transferred to their respective switches ASA, BSA, CSA. In order that switch AS may be in a position to receive the thousands digits it transfers its setting which resulted from the A digit, to certain relays W.X.Y.

80 85 The first junction selector FJS may be associated with a calling line in any convenient manner, as by being connected "back-to-back" with a line finder.

90 95 The second junction selector SJL is associated with a calling line by having the calling line extended to it over FJS by way of overflow links, if all direct junctions on FJS are busy and the call is one which can be reached by way of second choice junctions as described. If all direct junctions are busy and the call is one which cannot be so reached, busy signal is given 100 to the caller.

105 Selectors as FJS, SJL, FMS, MA have two sets of wipers and two sets of bank contacts shown respectively in full and dotted lines. The switches are arranged such that the wipers operate successively over their respective banks.

110 Switches like AS, etc., are provided with a number of wipers each of which operates over a bank of contacts. The normal contact will be referred to as N and the succeeding ones as 1, 2, 3, etc. A wiper will be referred to as in N or in 1 etc., meaning that it is in position N or position 1 etc.

115 The FJS which is to be used is determined by an allotter which in allotting an FJS for service, takes note of its busy or idle condition. The allotter is not shown and its manner of operation is not described herein as it forms no part of the invention and may be of any convenient type.

120 The idle condition of an FJS is indicated to the allotter by negative or wire P. The circuit for this negative is from battery over wipers BS5 and CS3, Fig. 2, in N, wire 1 Figs. 2 and 1 through various off-normal contacts, contact jb1, off-normal contact fjs on 2 to wire P.

125 When the line finder associated with FJS picks up a calling line, relay A operates in a circuit from earth by way of contacts lc1 Fig. 2, and s1 at rest, and so forth as may be easily seen.

130 Relay A has two contacts a1 and a2 this fact being indicated by the numeral 2 beneath its code letter. Of these, contact a1 serves for repeating subscriber-delivered impulses to FCC and contact a2 serves for repeating such impulses to SCC if necessary. For the present contact a2 may 135 be disregarded entirely as it is rendered ineffective in a manner which will later appear.

140 Contact a1, Fig. 2, when first operated closes a circuit for relay B which operates and remains operated in the well-known manner, until relay A shall remain released for a prolonged period.

145 Relay B prepares circuits as follows: at contact b1, Fig. 1, for holding relay K when eventually that relay shall operate; and at contact b2 for relay C and magnets of the various switches which circuit will be completed when impulsing shall be in progress. It closes a circuit at contact b4 for relay JB which operates. The effects of the operations of other contacts of relay B will be referred to in due time.

Relay JB operates and opens all its contacts j_1 to j_6 whereby all the first junction selectors served by FCC are rendered busy and the relay K of the FJS which is at present under consideration is operated in the test circuit already described.

Relay K operates and at contact k_1 closes the holding circuit already prepared by contact b_1 ; at contact k_2 connects earth to wire P to mark the FJS busy; and at its various other contacts couples the first junction selector circuit to the first common control.

Everything is now in order for the caller to commence dialling and this fact may be indicated to him by dialling tone in any convenient manner which need not be described herein.

The caller now dials and in response thereto relay A releases and re-operates. At the first release of relay A, contact a_1 closes the already prepared circuit for relay C as follows: earth, contacts a_1 , b_2 , relay C, t_03 and E_3 at rest, wiper AS1 in N, and magnet ASDM which is the driving magnet of digit switch AS, to negative battery.

Relay C and magnet ASDM operate in this circuit and relay C (which will remain operated until relay A shall be held operated during the inter-digital pause) at contact c_1 closes an alternative circuit for magnet ASDM, over which alternative circuit subsequent impulses will be delivered to that magnet: at contact c_2 isolates wipers AS2, BS3 and BS4 of the AB digit switches so that, whilst those switches are in motion (only switch AS is at present under consideration), no circuits may be completed thereover: and at contact c_3 , Fig. 1, places a short circuit around contact a_2 for the purpose referred to above. Contact c_4 will be referred to in due time.

As relay A reoperates, and subsequently releases and reoperates, switch AS is driven step-by-step under the action of magnet ASDM, the drive being effected on the release of that magnet.

The number of impulses delivered to magnet ASDM may be 1, any number above 1 and less than 10, or 10.

One impulse, as a first train, is not recognized and the effect of its receipt is to cause NU tone to be delivered to the caller. Thus, when relay C releases, after the delivery of one impulse, and the resultant stepping of switch AS into position 1, a circuit is completed from earth over contacts b_4 , Fig. 2, t_06 , c_2 , wiper AS2 in 1, winding (1) of relay SL to negative. Relay SL operates and at contact s_1 connects NU tone to the caller, the circuit being NU, s_1 , wire 2 and so on through relay A.

Ten impulses as a first train usually denote an "0" call, that is a call to an operator. Thus, when relay C releases after the delivery of ten impulses, and the resultant stepping of switch AS into position 10, a circuit is completed from earth, over contacts b_4 , t_06 , c_2 , wiper AS2 in 10, winding (1) of relay TM to negative. Relay TM operates and may, at contact t_01 , Fig. 1, cause the operation of relay WS if "0" calls are to be completed over the second wiper of switch FJS. At contact t_02 , relay TM closes a circuit from earth over contacts t_01 , t_01 , t_02 , t_01 , all at rest, t_02 and k_8 operate, for unlatch magnet FLM. Contact t_03 has no effect in an "0" call. Switch AS, at wiper AS5 in 10 effects the marking of the group of contacts in bank FG (or FG1) in which lines to the operator are situated.

Unlatch magnet FLM is the unlatch magnet of

switch FJS, and the effect of its operation is to unlatch the switch and to close, at its contact f_01 the circuit of the driving motor FDM of the switch FJS.

In response to the closing of the circuit of motor FDM, switch FJS is driven to find an idle outlet to the operator's position. As soon as it moves off normal it opens off-normal contact f_02 whereby the test circuit over which FJS was tested is opened at a second place (it was opened at contact a_02 as soon as switch AS moved off normal). Selector FJS continues to rotate until its wiper FG (or FG1) reaches the marked group of lines and until its wiper FP (or FP1) reaches an idle line within the group leading to the operator. When this happens a circuit is completed from earth through rectifier R, winding of quick acting relay TA, wiper AS5 in 10, wiper (say) FG, contacts w_5 , k_7 , w_4 , wiper FP, to negative on the test wire FPW of the idle operator-circuit.

Relay TA operates and, at its contact t_01 , opens the circuit of unlatch magnet FLM and closes a circuit for winding (I) of relay TD, this circuit being from earth over contacts t_01 , t_01 , t_02 at rest t_01 operated, winding (I) of relay TD, wiper AS5 in 10 and then as for relay TA to negative on wire FPW.

The unlatch magnet releases and opens the circuit of motor FDM and latches the switch.

Relays TD and TA, in parallel, lower the potential on wire FPW sufficiently to render the operator-circuit busy, and relay TD at contact t_02 closes a holding circuit for itself, at contact t_03 closes a second holding circuit for itself from earth over contacts b_7 , t_02 , winding (II) of relay TD, resistance w_1 to battery, and at contact t_03 closes a circuit from earth over contacts t_03 , and k_3 , and relay H to negative.

Relay H operates and at contact h_1 closes a holding circuit for itself, at contacts h_2 and h_3 connects incoming wires W_+ W_- to wipers F_+ , F_- , at contacts h_4 extends wire P through to wiper FP whereby earth is reverted, in a manner not necessary to be described, from wire FPW to maintain the busy condition on wire P, and at contact h_5 closes a holding circuit for relay WS if that relay should be operated. The calling line is now through to the idle operator circuit.

As a further result of the operation of relay H, the circuit of relay A is opened and this relay releases. Relay A, at its contact a_1 , Fig. 2 opens the circuit of relay B which releases. Relay B at contact b_1 , Fig. 1, opens the circuit of relay K, at contact b_2 (Fig. 2), opens the circuit of relay C, at contact b_4 opens the circuit of relay TM and at contact b_3 closes a homing circuit for switch AS. This homing circuit is as follows: earth, contact b_3 , wiper BS1 in N, off normal contacts c_01 at rest, and a_01 operated, interrupter contact $asdm$ of switch AS, contact g_8 at rest to magnet ASDM.

As soon as switch AS reaches its home position, it opens contacts a_01 and thus opens its own drive circuit.

Any number of impulses, other than 1 or 10, has a first train, denotes that a B and perhaps a C, digit should follow. Thus, when relay C releases, after the delivery of the A digit impulses and the resultant stepping of switch AS into a position which may be any of the positions 2-9 inclusive, a circuit is completed from earth over contacts b_4 , t_06 , c_2 , wiper AS2 in 2 (-9), contact e_1 winding (I) of relay E to negative. Relay E operates with results to be described.

As switch AS was moving to the desired position, 150

wiper AS4 encountered, in turn, contacts 2-9 and in 3-9 of these positions caused a relay, or a combination of relays W, X, Y to operate in a circuit from earth at contact b5, over contact e9 at rest, 5 and wiper AS4 in its successive positions. These relays operate in accordance with the following table.

10	Digit	AS position	Relays or windings
	2	2	None.
	3	3	W (I).
	4	4	Y (I).
	5	5	W (II) Y (I).
	6	6	X (I).
	7	7	X (I) Y (II).
15	8	8	W (III) X (I).
	9	9	W (III) X (I) Y (III)

Although these relays operate as wiper AS4 passes through the successive positions, they release as soon as the wiper leaves the positions on the way to that one at which it shall stop.

When, eventually, wiper AS4 comes to rest, the relay or combination of relays W, X, Y appropriate to the stopping position is not released.

25 Now to return to relay E and the effect of its operation. At contact e1 it closes a holding circuit for itself. At contact e2 it opens the circuit of relay TM so that when eventually switch AS may move to or through position 10, this relay will

30 not operate. At contact e3 it switches the impulse repeating circuit (contact a1) from magnet ASDM to magnet BSDM. At contact e7 (bottom left quarter of Fig. 2) it closes a circuit from earth over contacts b6, e7, t1, for the unlatch

35 magnet MLM of marking switch FMS. At contact e9 it closes a holding circuit for whichever relay, or combination of relays W, X, Y is operated, this circuit including a contact w1, x1 or y1, and winding (I) of the relevant relay (s).

40 Other contacts of relay E have no present effect.

Magnet MLM removes the latch from switch FMS (which is a marking switch and which is represented in Figs. 1 and 2 by various wipers and banks FMS and by its motor MDM) and at

45 mml1 closes the circuit of motor MDM.

Motor MDM drives wipers FMS until wiper FMS1 arrives at a contact which is cross-connected to the contact marked by wiper AS3, when a circuit is closed from earth over contact b5, 50 through quick relay T, wiper FMS1 in "marked", wiper AS3 in "marking" (that is 2-9) resistance w2, to negative. Relay T operates and opens the circuit of unlatch magnet MLM which releases and latches switch FMS in the position to which 55 it has been driven, the position being the beginning of a group of contacts appropriate to the A digit.

The operation of switch FMS is completed before impulses representing the B digit arrive.

60 Impulses representing the B digit are directed to magnet BSDM which drives its wipers to an appropriate position, the circuit being from earth over contacts a1, b2, relay C, contacts to3, e3 operated, and f2 at rest, BSDM, to negative. In

65 addition to effecting the drive of switch BS, the impulses cause the operation of relay C which remains operated until the end of the train of impulses. Contacts c2 and c3 have the same effect as previously. Contact c1 closes a circuit from

70 earth over contacts to8, c4, f3, c1, through magnet ASDM to negative. Magnet ASDM therefore energizes and remains energized during the reception of the B train of impulses.

75 Selector BS will be driven into one of its positions 2 to 10 in response to a B digit 2-0; Digit

1 is not used as a B digit. When switch BS arrives at, or passes through position 2 a circuit is completed from earth over contact b3, wiper BS2 in 2, wiper CS1 in N, contact *cadm*, and magnet CSDM to negative. Magnet CSDM operates, opens contacts *csdm*, releases, and as a result goes into a false normal shown as 0 where it rests. If the B digit be more than 5, as soon as the BS selector reaches position 6, the circuit for magnet CSDM is again completed the circuit now including wiper BS2 in 6-10 and CS1 in 0 to 11. Switch CS consequently self drives to position 12. The reason for driving switch CS during the setting of switch BS will be referred to later.

At the end of the train of impulses representing the B digit, relay C releases and, at contact c1, opens the circuit of magnet ASDM. The AS switch is thus moved to the position next to that to which it was set in response to the impulses, representing the A digit. One effect of this movement of AS is, at AS3, to open the circuit of relay T, which releases. Other effects will be referred to later.

Further effects of the operation of relay C are, at contact c2 a circuit is closed from earth over contacts b4, to6, c2, wiper BS4 in 2-10, winding (I) of relay F, to negative.

Relay F closes, at contact f1 a holding circuit for itself; at contact f2 switches the impulse repeating circuit from magnet BSDM to magnet CSDM; at contact f3 opens the circuit in which magnet ASDM was induced to take its extra step; at contact f5 connects winding (II) of relay SL to wiper AS3; at contact f6 closes a marking circuit to wiper BS6; and at contact f7 prepares a circuit for winding (I) of prepositioning relay PP. The function of relay PP will be referred to anon.

Relay T, which, as stated, released, closes at contact t1 a circuit for unlatch magnet MLM which removes the latch from marking switch FMS and closes the circuit of motor MDM of that switch. The marking switch therefore moves rapidly to find a contact within the group at the beginning of which its wiper FMS1 is standing, marked over wiper BS6.

When wiper FMS1 reaches the contact, which is the first contact of a sub-group of contacts within the group to the beginning of which it was moved in response to the marking over wiper AS3, relay T again operates and releases latch magnet MLM whereby switch FMS is brought to rest.

Switch FMS is now in a position which is determined by the combined setting of switches AS and BS, that is by the A and B digits. This position may be one, that is the A, B digits may be such that the second (dotted) wipers and bank contacts of switch FJS have to be utilized for routing the connection. In such cases there will be a cross-connection from the contact in bank FMS3, appropriate to the A, B digits, to relay PP.

When, therefore, switch FMS comes to rest, and as a further result of the operation of relay T, a circuit will be completed from earth over contacts b, e7, t1, g5, f7, wiper FMS3 in a position determined by the AS, BS marking, winding 1 of relay PP, to negative. Relay PP operates with results to be explained.

If a non-existent A.B. combination shall have been dialled there will be no connection from wiper BS6 in "marking" to the contact bank served by wiper FMS1, and as a result, relay T will find no circuit. Wiper FMS1 will therefore

80

continue in rotation until it reaches the last contact of the group to which it was set in response to the setting of wiper AS3. This last contact is, in fact, the first contact of the next group but this fact is immaterial. This last contact is marked by wiper AS3, which, it will be recalled, took an extra step after the release of relay C. In this last contact position a circuit is completed for relay T, and in series therewith, for winding (II) of relay SL over contact f5. Relay SL operates and, at contact s1 connects NU tone to the caller. No circuit is completed in the last contact position, over wiper FMS3 for relay PP.

Assuming that a setting of marking wiper FMS3 corresponding to a proper code has been effected, and that, because the call has to be routed over a dotted bank of switch FJS, relay PP has operated, relay PP, at contact pp1 closes a holding circuit for itself; at contact pp2, Fig. 1, closes a circuit for unlatch magnet FLM of the junction selector FJS, and at contact pp3 prepares a circuit for stopping selector FJS at the first contact of the arcs of contacts shown dotted. Magnet FLM removes the latch from selector FJS and closes the circuit of its motor FDM whereby the selector is driven rapidly to find the first contact above mentioned.

As soon as the first contact of the arcs of contacts shown dotted is reached, a circuit is closed from earth through rectifier R, relay TA, contact pp3, first dotted contact and dotted wiper FG, contacts ws5, k7, ws4, wiper dotted FP and first dotted contact, resistance w3 to negative.

Relay TA operates and at contact ta1 opens the circuit for the unlatch magnet which releases to open the motor circuit and latch the selector.

Meantime the caller is transmitting impulses representative of the C digit. These are effective on magnet CSDM and cause switch CS to be driven to an appropriate position. This position will be one of the positions 2-10 or 14-22 it being recalled that switch CS has already been driven to one of the positions false normal 0 or 12, and it being noted that 1 is not used as a C digit. During the reception of the train of impulses, relay C is operated, and at the conclusion of this reception relay C releases.

When relay C releases, a circuit is closed, from earth over contacts b4, to6, c2, wiper BS3 in 2-5 or 6-19, wiper CS2 in 2-10 or 14-22, contacts g1, winding (I) of relay G to negative. Relay G operates and at contact g1 closes a holding circuit for itself; at contact g2 switches the impulsive circuit from magnet CSDM to magnet ASDM for a purpose to be explained later; at contact g3 prepares a self driving circuit for magnet ASDM; at contact g4 opens the circuit, which passed over wiper BS6, of relay T, which releases; at contact g5 prepares a circuit for winding (II) of relay TM; and at contact g7, Fig. 1, connects winding (II) of relay PP into the circuit previously traced over wipers FG and FP of the pre-positioned selector FJS. Since the two windings of relay PP are in opposition, this relay releases and opens the circuit of relay TA which releases.

Relay T, on its release, closes the circuit of unlatch magnet MLM which, as before, unlatches marking switch FMS and closes the motor circuit. The marking switch rotates until its wiper FMS2 encounters a marked contact when a circuit is completed as follows: earth over contacts b5, relay T, wiper FMS2, in "marked", one of the wipers CS4, CS5, CS6, or CS7 in low B "marking" or CS3, CS4, CS5, CS6 or CS7 in high B

"marking", wiper BS5 in "distributing", which depends on the value of the B digit and may be 2-10, resistance w4, to negative. Relay T operates in this circuit and, at contact t1, opens the circuit of the unlatch magnet and closes a circuit for winding (II) of relay TM.

Relay TM operates and at contact tm1, Fig. 1 connects earth to wiper FMS4 whereby, if the outlet is to be found over the auxiliary wipers of selector FJS, relay WS is operated; at contact tm2, closes a circuit for selector unlatch magnet FLM which removes the latch from selector FJS and closes a circuit for its motor FDM, and at contact tm3, Fig. 2 closes the already prepared self drive circuit for magnet ASDM.

Selector AS self-drives in the circuit from earth over contacts to8, e4, f3, tm3, asdm, g3, wiper AS1 in 3 to 10 (it being recalled that switch AS has been set to a position 2-9 and has taken an extra step), magnet ASDM, to negative, and comes to rest in position 13.

The marking switch has, as a result of its various movements, been brought to a position where it can mark a contact in its bank FMS6 which is appropriate to a group of outlets from selector FJS which corresponds to the A. B. C. digits. This contact is cross connected to a group of contacts appropriate to the required group of outlets in bank FG (either full or dotted) or bank FG1 (either full or dotted). If the outlet is reached over bank FG or FG1 dotted, selector FJS is prepositioned and if it is reached over bank FG1 either full or dotted a corresponding contact in bank FMS4 is cross connected to relay WS. Moreover, if the destination to which the group of outlets lead is one which can be reached over an alternative route by way of second selector SJL, a corresponding contact in bank FMS5 is cross-connected to a group of contacts in bank FG or bank FG1 which is appropriate to a common group of overflow outlets.

There may, or may not be an idle outlet in the marked group, and if not, it may or may not be possible to complete the connection to an alternative route.

Let it first be assumed that there is an idle outlet. When the latch was removed from selector FJS, this selector rotated rapidly from its normal position, or from its prepositioned position on the first contact of the arcs shown dotted, until it arrives at the group of marked contacts and until it arrives at the first idle outlet in that group. When it reaches this position a circuit is completed from earth through rectifier R, winding of relay TA, wiper FMS6 in "marking", a group of marked contacts in bank FG (or bank FG1, say FG), wiper FG, contacts ws5, k7, ws4, wiper FP, the test wire of the first idle outlet (which may be considered to be wire FPW) to negative at the next stage.

Relay TA operates in this circuit and at ta1 opens the circuit of the latch magnet FLM, whereby the selector is brought to rest, and closes a circuit from earth over contacts to1, tb1, td1, ta1, operated, winding (I) of relay TD and then as above.

Relay TD operates and, at contact td1 closes a holding circuit for itself. The resistances of relays TA and TD in parallel are sufficiently low to mark the outlet busy. Relay TD, at contact td2 closes an alternative holding circuit for itself from earth, over contact b7, through winding (II) of relay TD, resistance w1, to negative and, at contact td3 closes a circuit for relay H which operates and at contact h1 closes a holding cir-

cuit for itself to wire P: at contacts *h2* and *h3* connects wires W+ and W- to wipers F+ and F-; at contact *h4* connects wire FPW through to wire P so that earth, eventually fed back from the next selector, may replace that at present provided by contact *k2*; and at contact *h5* closes a holding circuit for relay WS if that relay is operated. Relay H at contacts *h2* and *h3* also opens the circuit of relay A which releases.

10 The result of the release of relay A is as described at the end of the description below, of discharge from FCC of the A. B. C. digits and first numerical digit.

15 The connection will have been extended to the next stage, that is to the first numerical selector before the subscriber will have been able to dial the first numerical digit. The impulses representative of this digit will be received at that numerical selector.

20 When the connection is to be cleared, earth is removed from wire FPW in a manner not forming part of this invention, and being any suitable one of the known manners, not being described herein. The removal of this earth allows relay 25 H to release and relay H, at its contact *h5* opens the circuit of relay WS and closes a circuit from earth over contact *h5*, off normal contact *fjs*₀₁ contact *k3*, unlatch magnet FLM to negative. As soon as selector FJS reaches its home position 30 it opens contacts *fjs*₀₁ and so brings itself to rest by releasing unlatch magnet FLM and motor FDM.

Let it be assumed now that there is no idle outlet in the marked group and the connection is 35 not one which can be routed over an alternative route. In this condition there will be no circuit completed over wiper FMS6, for relay TA, and consequently the circuit for magnet FLM will be maintained. Due to this, switch FJS will continue

40 to rotate until its wipers reach the last contact in the arcs shown dotted whether the selector was prepositioned or not. Thereupon a circuit will be completed for rapid relay TA, from earth through rectifier R, relay TA, contact *pp3* at rest, 45 last dotted contact of bank FG (or bank FG1), the associated dotted wiper, contacts *ws5*, *k7*, and *ws4*, dotted wiper FP (or wiper FP1), the last dotted contact in the associated bank winding (II) of relay TD and relay LC, to negative. Relays TA and LC operate but relay TD does not 50 since upon the operation of relay TA, its two windings are in opposition, the circuit of winding (I) being completed at contact *ta1* as soon as relay TA operates. Relay LC, at contact (*lc1*, Fig. 2 connects busy tone to the caller and, as soon as he clears down, relay A releases and restores all apparatus to normal.

Let it be assumed now, that there is no idle outlet in the marked group, and that the connection is one that can be completed over an alternative route. For this purpose selector FJS has to rotate until its wipers reach a group of overflow outlets leading to a group of second junction selectors. Its continuing to rotate is, as in the immediately preceding paragraph, due to its wiper FP or FP1 not being able to complete a circuit for relay TA in the marked group. When, however, wiper FG1 arrives at the group of overflow links and wiper FP1 arrives at the contact of an idle such link, a circuit is completed from earth through rectifier R, winding of rapid relay TB, wiper FMS6 in "overflow marking" wiper FG or FG1 in "overflow marked", contacts *ws5*, *k7*, *ws4*, wiper FP or FP1, to negative on the test wire, similar to FPW, of the idle overflow link.

Relay TB operates and closes a circuit from earth over contacts *to1*, *tb1*, winding (I) of relay TO and then as above.

Relay TO operates and, at contact *to1* closes a holding circuit for itself; at contact *to2* Fig. 2, prepares an impulse circuit which will be more fully explained anon. At contact *to3* connects the *a1* impulse circuit directly to switch AS for a purpose to be described; at contact *to4*, Fig. 1 provides an alternative circuit for relay WS, if that relay should be operated, against the eventual release of relay TM; at contact *to5*, connects impulsive contact *a2* to wire W+ so that subsequent numerical impulses may be repeated to the second junction selector, as later described; at contact *to6*, Fig. 2 provides an alternative holding circuit for itself through its own winding (II); and at contacts *to7* and *to8* prepares operations which need not here be considered. The alternative holding circuit for relay TO is to guard against its release when, due to earth being fed back over wire FPW, its winding (I) is short circuited.

Had there been no idle overflow link, relay TB and relay TO would not have operated, and selector JFS would have rotated to its last dotted contact and relays TA and TD would have operated, all in the manner described for the case in which there was no direct outlet and alternative routing was not provided.

Certain differences should here be noted. When an idle direct outlet was found relay TD operated and led to the operation of relay H which switched the calling line through to the next stage, at which the first numerical train of impulses was received. When an idle overflow outlet is found, relay TO operates and does not lead to the operation of relay H. Consequently, subsequent numerical impulses are received on relay A.

An overflow outlet having been found, it is necessary to transfer the A. B. C. digits to the second common control SCC. This operation commences as soon as SCC is ready to receive the relevant impulses. The dialing of the first numerical digit is, however, in no way under the control of SCC and the caller may (through not necessarily would) commence this operation before, even with the very rapid selectors such as FJS, the SCC is ready to receive the impulses. For this reason it is arranged that when an overflow link and selector SJL is to be used, the first numerical digit shall always be received in the first common control apparatus and shall subsequently be transferred to SCC. This first numerical digit is received on switch AS, and it was for this reason that the A digit was cleared out of switch AS and stored on relays W.X.Y.

There are a number of concurrent operations that may take place at this stage, namely the first numerical digit may be received in FCC during the time that the A. B. C. code is being discharged; the A. B. C. code and first numerical digit will be, of course, discharged from FCC at the same time that it is being received in SCC, and the second, third and final numerical digits may be in course of reception by SCC during the time that SCC is receiving from FCC the A. B. C. code and first numerical digit. As it is difficult and, in any case, unsatisfactory to treat these concurrent operations concurrently, they will be treated separately in the order: reception of first numerical digit by FCC; discharge of A. B. C. code and first numerical digit from FCC; reception of A. B. C. code and first numerical digit by SCC; and reception of second etc., digits by SCC.

As the caller transmits the first numerical digit, relay A responds and, at contact *a*1 repeats these impulses to magnet ASDM, the circuit being by way of contacts *e*3, *f*2, *g*2, until relay TO operates when the circuit is by way of contact *to*3. The first impulse is by way of wiper AS1 in 13 and subsequent impulses are by way of contact *c*1. As, when relay TO operates, contact *a*2 is connected to wire W+, this contact is short circuited during the repetition of the first numerical impulses, first by wiper AS8 in 13 and later by contact *c*3. In response to the train of impulses representing the first numerical digit, switch AS is set into one of its positions 14-23. At the end of the train of impulses, relay C releases and cannot again operate, as in positions 14-24 there is no circuit for it. Consequently there will, for subsequent trains of impulses, be no short circuit across contact *a*2.

20 The manner in which the A. B. C. digits are discharged is as follows, it being recalled that a relay or combination of relays W X Y is operated whereby the A digit is stored; wipers BS, and in particular wiper BS7, are in a position 2-10, wipers CS and particularly wiper CS8, are in a position 2-10 or 14-22; and that wipers AS and particularly wiper AS7, will soon be in a position 14-23.

As soon as relay TO operated as a result of the finding of an idle overflow link, a circuit is completed from earth over machine interrupter contact M1, contacts *to*2 and *e*6, wiper SS1 in N to driving magnet SSDM whereby sending switch SS is driven out of position N. Successive impulses from contacts N1 are delivered directly, that is not over contact *e*6, to magnet SSDM whereby this switch continues to step until stopped at the conclusion of the transference of the A. B. C. digits.

40 When switch SS reaches position 1 a circuit is completed from earth over contact *b*8, wiper SS3 in 1, winding (I) of relay SZ, to negative. Relay SZ operates and, at contact *sz*1, closes a holding circuit for itself; at contact *sz*2 closes a circuit from earth over machine interrupter contacts M2, over wire 3 to wire W- whereby impulses are repeated to SCC; and at contact *sz*3 removes a short circuit from its winding (II). Contacts M1 and M2 interrupt their respective circuits in synchronism with the result that for each step of switch SS, an impulse is delivered to wire W- as long as contact *sz*2 is closed.

When switch SS has made a number of steps corresponding to the A digit stored on a relay or relay combination W.X.Y. a circuit is completed from earth over contacts *b*8, *e*5, *f*4, *g*6, through winding (II) of relay G, over appropriate contacts *w*, *x*, *y*, an appropriate counting wire CW, wiper SS2 in 3-11, winding (II) of relay SZ, resistance *w*5 to negative. Relays G and SZ release due to the completion of this circuit as their respective windings (I) and (II) are in opposition.

60 Due to the release of relay SZ, the delivery of impulses to W- is interrupted. Relay G, at contact *g*5 releases relay TM and at contact *g*6, switches out relay W.X.Y. and substitutes wiper BS7.

Switch SS continues to drive, the circuit for taking it through position 12 being over contact *e*3 and wiper SS1 in 12. In position 13 a circuit is again completed for winding (I) of relay SZ over wiper SS3 in 13.

75 The pause between the A and B trains of impulses is provided as switch SS passes from the

marked contact to position 13, and if the marked contact had been contact 11, would have been of two-impulse duration.

Eventually wiper SS2 encounters a marked contact in 14-23 and a circuit from earth is completed through windings (II) of relays F and SZ respectively. These relays release and relay SZ interrupts the delivery of impulses to wire W-. Relay F, at contact *f*4, switches out wiper BS7 and substitutes wiper CS8.

Switch SS continues to drive for a second revolution, the circuit for taking it through position N being over contact *e*6 and wiper SS1 in N. In position 1 a circuit is again completed for winding (I) of relays SZ over wiper SS3 in 1.

The pause between the B and C trains of impulses is provided as switch SS passes from the marked contact to position 2.

Eventually wiper SS2 encounters a marked contact 3-11 and a circuit is completed from earth over windings (II) of relays E and SZ. These relays release and relay SZ interrupts the delivery of impulses to wire W-. Relay E, at contact *e*5, switches out wiper CS8 and switches in wiper AS7; at contact *e*8 opens the circuit over which switch SS was driven through position 12; at contact *e*6 prepares a circuit for relay CO; and at contact *e*9 opens the holding circuit of relays W.X.Y.

Switch SS continues to drive until it reaches position 12. Whether it shall drive through position 12 or not will depend on whether the caller has commenced and finished to dial the first numerical digit. Assuming that he has commenced, switch AS will have left position 13, and assuming that he has finished, relay C will be released. In this case the driving circuit for switch SS is from earth over contacts M1, *to*2, *c*4, wiper AS6 in 14-23, contact *e*8 at rest, wiper SS1 in 12, magnet SSDM to negative.

Eventually wiper SS2 encounters a marked contact 14-23, and a circuit is completed from earth over winding (II) of relay SZ. Relay SZ releases and terminates the delivery of impulses to wire W-.

Switch SS continues to drive until it reaches position N. Beyond this position it cannot again be driven as its circuit is open at contact *c*6. In this position, a circuit is completed from earth through relay CO, over contacts *to*7 and *e*, wiper SS1 in N and magnet SSDM to battery. Relay CO operates but magnet SSDM does not do so.

Relay CO, at its contact *c*1, Fig. 1, closes a circuit for relay H which operates and connects the caller through to the secnd junction selector and cuts out relay A. Relay A releases and causes the release of relay B whereby relay JB is released to short-circuit relay K, and the holding circuit of relay K is opened.

Switch BS is self-driven home in a circuit from earth over contact *b*3, wiper BS1 in 1-24, interrupter contact *bsdm*, magnet *bsdm*, to negative. When wiper BS1 is in N, a circuit is completed from earth over contact *b*3, wiper BS1 in N, off-normal contacts *cson*1, interrupter contact *csdm*, magnet *csdm* to negative. Switch CS therefore is self-driven to normal. When switch CS is in its normal position, a circuit is completed from earth over contact *b*3, wiper BS1 in N, off-normal contacts *cson*1 at rest, *asdn*1, interrupter contact *asdm*, contact *g*3, magnet ASDM, to negative.

Switch AS is thus self driven to normal. Relay B, when it released also at contact *b*6 completed a circuit from earth over *b*6, off-normal contact *fmson* unlatch magnet MLM to negative.

Magnet MLM unlatches marking switch FMS and closes a circuit for motor MDM whereby the marking switch is driven to its home position where it opens the circuit of the unlatch magnet MLM. The common control apparatus is now in its normal condition and is, due to the release of relay K, dissociated with the junction selector FJS.

- The operation of second junction selector SJL 10 and of the second common control apparatus SCC and particularly the reception of the A. B. C. digits will now be described. A few notions must, however, be carried forward from the preceding description (1) earth through rectifier R, relay 15 TB to wiper FMS5, and over contact *to1*, relay TO to wiper FMS5, is extended by way of wiper FG (or FG1) contacts *ws5*, *k7*, *ws4*, wiper FP (or FP1), to wire FPW (or FPW1) which is continued in Fig. 3 as FPW; (2) as soon as relay 20 TO operated, on the finding of an idle second junction selector SJL, negative was connected to wiper F+ (or F+1) and thus to wire WA+ (or WA+1) which is continued in Fig. 3 as WA; (3) the negative referred to in (2) will eventually 25 be interrupted (impulsed) at contacts *a2* by the caller for the second to final numerical digits; (4) each time relay SZ (winding I) operated, earth impulses for the A. B. C. digits, and first numerical digit, were transmitted over wiper F- (or F-1) and thus to wire WA- (or WA-1) which is continued in Fig. 3 as WA-.

The negative on wire WA+ Fig. 3, passes over contact *ha2*, relay AS, contact *lc1* to earth and relay AS operates. The earth on wire FPW 35 passes over contacts *sjs0n2*, *ja1*, a series of off-normal contacts, wipers CSA2 in N Fig. 4 and BSA3 in N, resistance O1, to negative. This is the circuit over which the outlet was tested. The earth on wire WA- passes over contact *ha3*, 40 through relay AA, to negative. Relays AS and AA operate, and the former, at contact *as1*, Fig. 5 closes a circuit for relay BA which operates.

Relay BA, at contact *ba1*, prepares a circuit which will be referred to later; at contact *ba2*, 45 closes circuits from earth over contact *ba2*, through auxiliary winding (I) of relay D to negative, and from earth over contact *ba2* over wiper BSA5 in N, through relay JA to negative; at contact *ba3*, Fig. 4, prepares a circuit which will 50 be referred to later; at contact *ba4*, Fig. 3, prepares a holding circuit for relay KA, not yet operated; and at contacts *ba5* and *ba6* prepares circuits.

Relay JA removes the short circuit from relay 55 KA, whereby that relay operates and, at contact *ka1* closes its own holding circuit. Relay KA, also, at contact *ka2* reverts earth to the preceding selector, and at its other contacts couples the junction to the second common controller SCC.

60 Impulses representing the A, B, C and first numerical digit, and consisting of interrupted earth on wire WA-, cause relay AA to release and re-operate. Relay AA consequently at its contact *aa1*, Fig. 5, repeats the trains of impulses to magnets ASAM, BSAM, CSAM and MSAM, the circuit including wiper MS1, which acts as a distributor to distribute the successive trains of impulses to the appropriate magnet. The impulsive circuit also includes relay CC which operates during the impulsive, and releases between trains. Relay CC, at contact *cc1*, therefore brings about, by alternately closing and opening the circuit of magnet MSAM, the stepping of switch MS whilst that switch is acting as a distributor. The 75 stepping circuit for stepping switch MS from N

to 1, from 1 to 2, and from 2 to 3 is from earth over contact *ba2*, wiper MS2 in N, 1 and 2 respectively, contact *cc1*, and magnet MSAM to negative. The circuit for stepping switch MS from position 3 to 4, in response to the first digit 80 of the first numerical train is from earth, over contact *aa1* relay CC, wiper MS1 in 3, and MSAM, and for stepping it for subsequent impulses of the same train is over wiper MS1 in 4-13 and contact *cc1*. Relay CC, at contact *cc2* isolates 85 wiper MS4, so that during the setting of this switch for the first numerical digit, no circuit shall be completed over wiper BSA4, etc.

It is thought that a description of the operation of switches HS, TS and US, in response to the hundreds, tens and units impulses respectively, which are received on relay AS, it may be concurrently with the receipt of the A. B. C. digits and thousands digit, is not necessary as it is similar in every way to the operation of switches ASA, 95 BSA, CSA and MS. Wiper U1 acts first as a distributor and then as a register in the same manner as did wiper MS1.

During the setting of switches ASA, BSA, CSA 100 in response to the transferred A. B. C. digits, certain operations have taken place automatically. Thus when, in its course of being set in response to the B digit, switch BSA passes through position 1, a circuit is completed from earth over contacts *co2*, *tf2*, wiper BSA2 in 1, wiper CSA1 105 in N, driving contact *csam*, magnet CSAM to negative. Switch CSA therefore self-drives from position N to false normal position. If the B digit is more than 5, a circuit similar to the above is completed to cause switch CSA to self drive 110 from position 0 to position 12. The reason for this is similar to that for the corresponding switch CS in FCC. When switch MS steps from position 2, after the recording of the C digit, to position 3 for the recording by transfer from FCC 115 of the first numerical digit, a circuit is completed from earth over contact *ba2*, wiper MS2 in 3, contact *te1*, unlatch magnet MALM to negative. Magnet MALM operates, and unlatches marking switch MA and closes a circuit at contact *malm1*, 120 Fig. 4, for motor MADM. Motor MADM drives the marking switch until that switch occupies a position appropriate to the A. B. C. digits. When this position is reached, a circuit is closed from earth over contact *ba3*, quick relay TE, wiper ASA2 in "A group marking", MA1 in "A group marked" MA2 in "C contact marked", one of the wipers CSA in "C contact" and "B sub-group marking", wiper BSA3 in a "B sub-group marking", resistance O1, to negative. Relay TE operates and at contact *te1* opens the circuit of unlatch magnet MALM whereby switch MA is stopped. As soon as switch MA goes off normal, 125 it closes at contact *maon1*, a circuit which is independent of wiper MS2. This is because wiper MS2 may soon be driven in response to the first numerical digit.

Relay TE, in addition to opening at contact *te1* the circuit of magnet MALM closes a circuit for relay TF. Relay TF, at contact *tf1* closes a holding circuit for relay TE.

As the A. B. C. digits are now recorded on switch MA switches ASA, and BSA are relieved for other functions, ASA acting as a counting switch, and BSA as a distributing switch. Thus, when relay TF operated it closed at contact *tf2*, a circuit from earth at contact *cc2*, over contact *tf2*, wiper ASA1 which may be in any position 2-8 (or in position 9 in which position the circuit will not be closed), driving contact *asam*, magnet 145 MSAM to negative. This completes the recording of the first numerical digit.

ASAM, to negative. In this circuit, switch ASA drives to position 9. Relay TF also at contact *tf2* closes a circuit over wiper BSA1 in 2-10, contact *bsaon* operated, drive contact *bsam*, magnet 5 BSAM, whereby switch BS self-drives to position 11.

Relay TF, at contact *tf3*, Fig. 3, closes a circuit from earth, over contact *tg1*, *th1*, *tt1*, *tk1*, *tf3*, *ka8* unlatch magnet SLM, to negative. Magnet SLM 10 operates and in the now well understood manner causes the selector SJL to rotate in search of a free outlet in the desired direction. The group of outlets may be marked in either of the banks SG or SG1. In the former case, relay WAS is not 15 to be operated, and in the latter it is to be operated. Further there may or may not be a free direct outlet, and the destination may be one which can be reached directly from SJL only, or directly preferably, and via a tandem exchange 20 if there are no direct outlets.

Let it be assumed that the operation of relay WAS is not required and that there is a free outlet. There will be an appropriate cross connection from wiper MA3, in the position to which it has been set, to a group of contacts in bank SG. 25 When a free outlet is found, a circuit will be completed from earth through rectifier RA, rapid relay TH, wiper MA3 in "marking", wiper SG in "marked", contacts *was5*, *ka7*, *was4*, wiper SP to wire SPW which is the test wire of the idle outlet. Relay TH, operates, and at contact *th1*, opens the circuit of the unlatch magnet and closes a circuit for relay winding (I) of TG. Relay TG operates and, at contact *tg1*, closes a holding circuit; at contact *tg2*, closes an alternative holding circuit for itself over winding (II); contact *tg3* Fig. 5 closes a self-drive circuit for advancing switch BSA from position 11 to position 16: and at contacts *tg4* and *tg5*, Fig. 3, closes 30 a loop across the wipers S+ and S-, this loop including wiper ASA5 in 9, and winding (II) of shunt field relay D.

At this stage, if the thousands digits have been received by switch MS, impulses would be transmitted over wipers S+ and S-. It is convenient, 45 however, to reserve the consideration of the manner in which this is effected, and to consider what happens if all outlets were busy; what happens if the outlets are in a bank which requires the operation of relay WAS; what happens if all outlets there are busy; and how a tandem outlet is reached.

If wiper SP finds no free outlet at the same time that wiper SG is moving over a marked group of contacts, or if wiper SG encounters no marked group (by reason of the group being marked in bank SG1) there will be no circuit for relay TH until switch SJL is driven to such a position that its dotted wipers reach the last contact in the 50 dotted arc of contacts. In this position a circuit will be completed from earth, over rectifier RA, winding (I) of relay TH, wiper SG in "last dotted", contacts *was5*, *ka7*, *was4*, wiper SF in "last dotted", winding (II) of relay TG, and winding (I) of relay S to negative. Relay TH operates and, at contact *th1* opens the circuit of unlatch magnet SLM and closes a circuit for winding (I) of relay TG. The two windings of relay TG are now in opposition so that this relay 55 does not operate, but relay S does and, at contact *s1* closes a holding circuit for itself through its winding (II) Fig. 5. It also at contact *s2*, Fig. 3, closes a circuit for relay WAS. Relay WAS operates, and at contact *was1* prepares a holding circuit for itself; and at contacts *was2*—

was5, switches over the wipers of selector SJL. By the changeover of contacts *was4* and *was5*, the circuit of relay TH is opened, and this relay releases.

Now, although wipers SP1 and SG1 are in "last dotted", yet no circuit is completed for relay TK, since this relay must be understood to be connected to the last but one dotted contact of arc SG1. When, therefore, relay TH releases, the circuit for unlatch magnet SLM is reclosed and selector SJL is driven in search of a free outlet in a marked group.

If this drive is being effected because, although a group was marked in bank SG, no free outlet was found, selector SJL will not find a marked group of direct junctions but will find a mark on a group of contacts appropriate to a tandem route. In this case it will be to find an idle outlet to the tandem centre over which the alternative route can be set up. If the drive is being effected for the purpose of finding an idle outlet in a direct group that is marked, not in banks SG, but in bank SG1, the drive will continue until such outlet is found, if one exists. If no free outlet exists the drive will continue to find a free outlet to the tandem centre. If no idle outlet to the tandem apparatus exists, the drive will be a restoring drive.

Let it be assumed that an idle outlet exists in a group of direct outlets, marked in bank SG1. In this case, as soon as the first idle outlet is reached by wiper SP1, a circuit is completed from earth over rectifier RA, relay TH, and so on as before, to wire SPW1. The selector is consequently brought to rest in association with the selected outlet and relay TG operates with the results already described.

Now let it be assumed that there is no idle direct outlet. There will be, in addition to the marking of the direct group, a marking of a common group of outlets leading to the tandem centre. As soon as an idle tandem outlet is found, a circuit will be completed from earth through rectifier RA, rapid relay TK, cross connection from terminal TN to the group of contacts in bank SG1 appropriate to the tandem route, wiper SG1, contacts *was5*, *ka7*, *was4*, wiper SP1, to a test wire similar to SPW1. Relay TK operates and at its contact *tk1* releases the unlatch magnet and closes a circuit for winding (I) of relay TT which operates. Relay TT, at contact *tt1* closes a holding circuit for itself; at contact *tt2* closes an alternative holding circuit from earth, over contacts *ba5*, *tt2*, winding (II) of relay TT, resistance S2, to negative; at contact *tt3* prepares a circuit for causing the transmission of tandem impulses as will be described, and at contacts *tt4* and *tt5* places a loop across the outlet, this loop including winding (II) of shunt field relay D.

If there were no idle tandem outlet, relays TK and TT would not find a circuit as selector SJL went through the tandem group, and the switch would continue to drive until dotted wiper SG1 reached the last but one dotted contact. In this position, selector SJL completes a circuit from earth, through rectifier RA, relay TK last but one dotted contact of wipers SG1 and SP, winding (II) of relay TT, and relay LC. Relays TK and LC operate but relay TT does not do so, as upon the operation of relay TK, the two windings of relay TT are connected differentially. Relay TK causes selector SJL to come to rest and relay LC at contact *lc1* reverts busy tone to the caller. The caller should replace his receiver whereby

relays AA and AS will release with results described later.

Assuming that there is an idle outlet, the transmission of impulses from SCC, to operate the next selector, now takes place. One or other of two conditions may exist, either the connection was extended over a direct outlet and relay TG was operated, or it was extended over a tandem outlet and relay TT was operated. In the former case impulses for operating the numerical selectors are transmitted immediately; in the latter, impulses for operating up to five code selectors at the tandem centre, or, if more than one tandem exchange is involved, centres are transmitted followed by the impulses for operating the numeral selectors.

Considering the former case first; when, due to the operation of relay TG, contact *tg3*, Fig. 5, closed and caused switch BSA to self-drive to position 16; and when either thereafter or already selector ASA goes to position 9 following the setting of marking switch MA, and when, moreover, the first numerical digit has been received on switch MS and relay CC has released, all as already described, a circuit will be completed from earth over contacts *ba2*, *cc2*, wipers MS4 in 4-13, BSA4 in 16, ASA3 in 9, contact *d1* (relay D being unoperated if the numerical selector to which the connection is so far extended is ready to receive impulses and is therefore reverting current in the correct direction to winding (II) of relay D, winding (I) of relay SZA to negative. Relay SZA operates, and at contact *sza1*, closes a holding circuit for itself (earth at contact *ba2*).

Relay SZA, at contact *sza2*, connects winding (II) of relay SZA to wiper ASA4; at contact *sza3*, Fig. 3, short circuits winding (II) of relay D and removes a loop from across the outlet (an alternative loop, however, exists over wiper ASA5 in 9); at contact *sza4*, Fig. 5, closes a driving circuit from earth, over contacts *co2*, *tf2*, *sza4*, impulsive contacts M3, for magnet ASAM; at contact *sza5*, opens the self driving circuit which exists over ASA1 in 10-20; and at contact *sza6* closes a circuit for magnet BSAM.

Switch ASA is driven in response to impulses from contact M3, and when it moves from position 9 it removes the short circuit which existed over wiper ASA5 so that impulsive contacts M4, which operate synchronously with contacts M3, transmit impulses over the loop. As wiper ASA4 rotates it searches for a contact marked in accordance with the setting of wiper MS3 that is in accordance with the value of the thousands digit. When such a contact is found, a circuit is completed from earth, over contacts *ba2*, wipers BSA5 in 16, MS3 in "marking", ASA4 in "marked", contact *sza2*, winding (II) of relay SZA to battery. The two windings of relay SZA being in opposition, this relay releases and, at contact *sza3* short circuits impulsive contacts M4; at contacts *sza4* opens the impulsive circuit for switch ASA; at *sza5* connects magnet ASAM into a self-drive circuit to take switch ASA to position 21; and at contact *sza6* opens the circuit of magnet BSAM so that this switch goes to position 17.

Switch ASA is impulse driven from position 21 to N, and self-driven from N to 9 where, if, or as soon as the hundreds numerical selector to which the connection is now extended is ready to receive impulses and is reverting current in the correct direction and relay D is therefore still (or again) released, and if the tens digit has

been dialled by the caller, a circuit is completed from earth, over contacts *ba2*, wiper TS1 of the tens switch in 1-10, BSA4 in 17, ASA3 in 9, contact *d1*, relay SZA, to negative. Relay SZA again operates and permits the transmission of the hundreds digit in the same manner as the thousands were transmitted, wiper HS1 in "marking" being involved.

At the end of this transmission, switch ASA is again driven to position 9 and switch BSA is driven to position 18. If the units digit has been received and relay D is again unoperated, the circuit for relay SZA is again completed, this time over wiper US2 in 3-12. Relay SZA again operates and permits the transmission of the tone impulses.

At the end of this transmission, switch ASA is again driven to position 9 and switch BSA is driven to position 19. The units digit having been received, relay SZA again operates and permits the transmission of the units digit.

At the end of the units transmission, relay SZA releases as before, and at contact *sza6*, drive switch BSA into position 20. When switch ASA, on its way from position 21 to N, reaches position 24, a circuit is completed, from earth at contact *ba2*, over wiper ASA3 in 24, wiper BSA4 in 20, relay CO to negative. Relay CO operates, and at contact *co1*, Fig. 3, closes a circuit for relay HA whereby the connection between the caller and the numerical selectors is completed and the circuit for relays AS and AA is broken. These relays release and cause the release and restoration to normal of SCC. Contact *co2* opens the stepping circuit of switch ASAM which rests awhile in 24.

The manner in which, if a tandem route is involved, impulses representing the A. B. C. digits are transmitted is as follows, it being, of course, understood that the number of impulses transmitted or number of trains need bear no numerical relationship to those received.

Owing to the non-operation of relay TG, Fig. 3, contact *tg3*, Fig. 5, is not closed and therefore switch BSA does not immediately self drive from position 11 to position 16 but, instead, rest in 11 for the present. Owing to the operation of relay TT instead of relay TG, contact *tt3* is closed and provides a circuit from earth, over contacts *ba2*, *tt3*, wiper BSA4 in 11 and ASA3 in 9, for relay SZA which operates and sets switch ASA into motion as above described.

Relay SZA releases when wiper ASA4 reaches a contact marked from earth, over wiper BSA5 in 11, wiper MA4 of the marking switch in 130 "marking", cross connecting field CF and so on. The release of relay SZA causes all the effects already described, including the stepping of switch BSA from position 11 into position 12.

This process continues until all the trains of digits representing the translated A. B. C. code have been transmitted when switch BSA will be in position 16, the position from which numerical transmission commences. If the translated A. B. C. codes does not involve the transmission of five trains of impulses the marked contact in one of the banks MA4 to MA8 will be cross-connected to relay SD. When, therefore, wiper BSA5 reaches a position which leads to the MA wiper thus cross-connected, relay SD operates, 145 and at contact *sd1* closes a holding circuit for itself and at contact *sd2* closes a self-drive circuit for switch BSA which self-drives to position 16 from which numerical transmission commences.

- It may be that, after the setting of one selector in response to impulses transmitted from impulse contact M4, a succeeding switch is not ready for response to a succeeding train of impulses.
- 5 To guard against the premature transmission of impulses, it is arranged that, until a switch is ready, battery is fed back over wipers S+ and S- (or S+1 and S-1) is in reverse direction whereby shunt field relay D is operated. Thus when 10 wiper ASA3 is in 9, the operation of relay SZA is delayed until relay D shall release due to the correction of the direction of the current fed back.
- Sequential restoration of the switches is effected as soon as relay BA releases, the circuit being from earth over contact ba2 and the various off normal and self-drive contacts such as hson1, hsam; tson1, tsam; uson, usam; mon1, mem; cson1, csam; and so on. The drive for switch MA 15 is from earth, over contact maon, contact te1, magnet MALM, to negative, relay TE releasing due to the release of contact ba3.
- We claim:—
1. In a multi-office telephone system, a main exchange, a plurality of other exchanges, groups of junction lines directly connecting each exchange with said main exchange, a first selector in said main exchange having access to a part of each group of said junction lines, overflow junction lines accessible to said first selector, auxiliary selectors in said main exchange connected to said overflow junction lines, and additional junction lines of said first junction groups accessible to said auxiliary selectors. 20
2. In a multi-office telephone system, a main exchange, a plurality of other exchanges, groups of junction lines directly connecting each exchange with said main exchange, a first selector in said main exchange having access to a part of some groups of said junction lines, a group of common overflow junction lines accessible to said first selector, auxiliary selectors in said main exchange connected to said overflow junction lines, and different junction lines of said first groups of junction lines accessible to said auxiliary selectors. 25
3. In a multi-office telephone system, a main exchange, a plurality of other exchanges, individual groups of junction lines connecting said exchanges with said main exchange, first selectors in said main exchange having access as an early choice to said individual groups of junction lines, a group of common overflow junction lines accessible to said first selector, auxiliary selectors in said main exchange connected to said overflow junction lines, and a group of later choice junction lines of said individual groups of junction lines accessible to said auxiliary selectors. 30
4. In a multi-office telephone system, a main exchange, a tandem exchange, a plurality of other exchanges, individual groups of junction lines connecting said other exchanges with said main exchange, first selectors in said main exchange having access to a first choice of said individual groups of junction lines, a group of overflow junction lines accessible to said first selector, auxiliary selectors in said main exchange connected to said overflow junction lines, a group of second choice junction lines of said individual junction groups accessible to said auxiliary selectors, and a group of tandem junction lines extending to said tandem exchange also accessible to said auxiliary selectors. 35
5. In a multi-office telephone system, a main exchange, a plurality of other exchanges, individual groups of junction lines connecting said other exchanges with said main exchange, first selectors in said main exchange having access to a first choice of said individual groups of junction lines, a group of overflow junction lines accessible to said first selector, auxiliary selectors in said main exchange connected to said overflow junction lines, a group of second choice junction lines of said individual junction groups accessible to said auxiliary selectors, common control apparatus for operating said first selectors in accordance with a plurality of digits designating an exchange to select an idle first choice junction line leading to such exchange, and means for transferring and utilizing said code routing designation to selectively operate said auxiliary selectors to select an idle second choice junction line. 40
6. In a multi-office telephone system, a main exchange, a plurality of other exchanges, groups of junction lines connecting each exchange with said main exchange, first selectors in said main exchange having access to a first choice of said groups of junction lines, a group of common overflow junction lines accessible to said first selectors, auxiliary selectors in said main exchange connected to said overflow junction lines, a group of second choice lines of said first junction group accessible to said auxiliary selectors, common control apparatus for operating said first selectors in accordance with the registration of a set of controlling digits to select an idle first choice junction line or an idle one of said common overflow junction lines, and means operated in case the overflow junction line is used for transferring the controlling digits from said common control apparatus over said overflow junction line to control said auxiliary selectors to select an idle one of said second choice junction lines. 45
7. In a multi-office telephone system, a main exchange, a plurality of other exchanges, groups of junction lines connecting each exchange with said main exchange, first selectors in said main exchange having access to a first choice of said groups of junction lines, a group of common overflow junction lines accessible to said first selectors, auxiliary selectors in said main exchange connected to said overflow junction lines, a group of second choice lines of said first junction group accessible to said auxiliary selectors, common control apparatus for operating said first selectors in accordance with the registration of a set of controlling digits to select an idle first choice junction line or an idle one of said common overflow junction lines, means operated in case the overflow junction line is used for transferring the controlling digits from said common control apparatus over said overflow junction line, and other common control apparatus operated responsive to said controlling digits from said overflow junction line for controlling said auxiliary selectors to select an idle one of said second choice junction lines. 50
8. In a multi-office telephone system, a main exchange, a plurality of other exchanges, groups of junction lines connecting each exchange with said main exchange, first selectors in said main exchange having access to a first choice of said groups of junction lines, groups of common overflow junction lines accessible to said first selectors, auxiliary selectors in said main exchange connected to said overflow junction lines, groups of second choice junction lines accessible to said auxiliary selectors, common control apparatus for operating said first selectors to select an idle first choice junction line, other common control apparatus for operating said first selectors to select an idle first choice junction line, and other common control apparatus for operating said first selectors to select an idle second choice junction line. 55

- trol apparatus for operating said auxiliary selectors to select an idle second choice junction line, both of said common control apparatus operated responsive to the reception of digits designating an exchange and to register and convert said digits into a marking condition in the banks of either said first or said auxiliary selectors.
9. In a multi-office telephone system, a main exchange, a plurality of other exchanges, groups of junction lines connecting each exchange with said main exchange, first selectors in said main exchange having access to a first choice of said groups of junction lines, groups of common overflow junction lines accessible to said first selectors, auxiliary selectors in said main exchange connected to said overflow junction lines, groups of second choice junction lines accessible to said auxiliary selectors, common control apparatus for operating said first selectors to select an idle first choice junction line, other common control apparatus for operating said auxiliary selectors to select an idle second choice junction line, each of said common control apparatus operated responsive to the reception of digits designating said exchange and to register and convert said digits into marking condition in the banks of said first and said auxiliary selectors, said first selectors operated to the marked bank to select an idle first choice junction line corresponding to the registered digit or to an idle one of said overflow junctions, a tandem exchange, tandem junctions accessible to said auxiliary selectors, said auxiliary selectors operated to the marked bank to select an idle second choice junction line corresponding to the registered digits or to an idle one of said tandem junctions in case the connection must be completed over said tandem exchange.
10. In a multi-office telephone system, a main exchange, a plurality of other exchanges, groups of junction lines connecting each exchange with said main exchange, first selectors in said main exchange having access to a first choice of said groups of junction lines, groups of common overflow junction lines accessible to said first selectors, auxiliary selectors in said main exchange connected to said overflow junction lines, groups of second choice junction lines accessible to said auxiliary selectors, common control apparatus for operating said first selectors to select an idle first choice junction line, each of said common control apparatus operated responsive to digits designating a desired exchange to effect two simultaneous markings in the bank of the corresponding selector, one of said markings indicating a group of first choice junction lines of the desired exchange and the other marking indicating the common overflow junction group in the case of the first selector, while in the case of the auxiliary selector one of said markings indicates the second choice junction lines and the other marking further junction lines to a tandem exchange.
11. In a multi-office telephone system, a main exchange, a plurality of other exchanges, groups of junction lines connecting each exchange with said main exchange, first selectors in said main exchange having access to a first choice of said groups of junction lines, groups of common overflow junction lines accessible to said first selectors, auxiliary selectors in said main exchange connected to said overflow junction lines, groups of second choice junction lines accessible to said auxiliary selectors, common control apparatus for operating said first selectors to select an idle first choice junction line or an idle one of said common overflow junction lines, means operated in case the overflow junction line is used for transferring the controlling digits from said common control apparatus over said overflow junction line, and other common control apparatus operated responsive to said controlling digits from said overflow junction line for controlling said auxiliary selectors to select an idle one of said second choice junction lines, and means in said selector common control apparatus for rendering the numerical digits directly effective from said first selector to the desired exchange without registration at said control apparatus.
12. In a multi-office telephone system, a main exchange, a plurality of other exchanges, groups of junction lines connecting each exchange with said main exchange, first selectors in said main exchange having access to a first choice of said groups of junction lines, a group of common overflow junction lines accessible to said first selectors, auxiliary selectors in said main exchange connected to said overflow junction lines, a group of second choice lines of said first junction group accessible to said auxiliary selectors, common control apparatus for operating said first selectors in accordance with the registration of a set of controlling digits to select an idle first choice junction line or an idle one of said common overflow junction lines, means operated in case the overflow junction line is used for transferring the controlling digits from said common control apparatus over said overflow junction line, and other common control apparatus operated responsive to said controlling digits from said overflow junction line for controlling said auxiliary selectors to select an idle one of said second choice junction lines, and means in said selector common control apparatus for rendering the numerical digits directly effective from said first selector to the desired exchange without registration at said control apparatus.
13. In a multi-office telephone system, a main exchange, a plurality of other exchanges, groups of junction lines connecting each exchange with said main exchange, first selectors in said main exchange having access to a first choice of said groups of junction lines, a group of common overflow junction lines accessible to said first selectors, auxiliary selectors in said main exchange connected to said overflow junction lines, a group of second choice lines of said first junction group accessible to said auxiliary selectors, common control apparatus for operating said first selector in accordance with the registration of a set of controlling digits to select an idle first choice junction line or an idle one of said common overflow junction lines, means operated in case the overflow junction line is used for transferring the controlling digits from said common control apparatus over said overflow junction line, and other common control apparatus operated responsive to said controlling digits from said overflow junction line for controlling said auxiliary selectors to select an idle one of said second choice junction lines, and means in said selector common control apparatus for rendering the numerical digits directly effective from said first selector to the desired exchange without registration at said control apparatus.
14. In a multi-office telephone system, a main exchange, a plurality of other exchanges, groups of junction lines connecting each exchange with said main exchange, first selectors in said main exchange having access to a first choice of said groups of junction lines, a group of common overflow junction lines accessible to said first selectors, auxiliary selectors in said main exchange connected to said overflow junction lines, a group of second choice lines of said first junction group accessible to said auxiliary selectors, common control apparatus for operating said first selector in accordance with the registration of a set of controlling digits to select an idle first choice junction line or an idle one of said common overflow junction lines, means operated in case the overflow junction line is used for transferring the controlling digits from said common control apparatus over said overflow junction line, and other common control apparatus operated responsive to said controlling digits from said overflow junction line for controlling said auxiliary selectors to select an idle one of said second choice junction lines, and means in said selector common control apparatus for rendering the numerical digits directly effective from said first selector to the desired exchange without registration at said control apparatus.

- junction lines, and means in said selector common control apparatus for rendering the numerical digits directly effective from said first selector to the desired exchange without registration at said control apparatus, said selector common control apparatus receiving and registering a predetermined number of numerical digits in case no idle first choice junction line is found by said first selector.
14. In a multi-office telephone system, a main exchange, a plurality of other exchanges, groups of junction lines connecting each exchange with said main exchange, first selectors in said main exchange having access to a first choice of said groups of junction lines, a group of common overflow junction lines accessible to said first selectors, auxiliary selectors in said main exchange connected to said overflow junction lines, a group of second choice lines of said first junction group accessible to said auxiliary selectors, common control apparatus for operating said first selectors in accordance with the registration of a set of controlling digits to select an idle first choice junction line of an idle one of said common overflow junction lines, means operated in case the overflow junction line is used for transferring the controlling digits from said common control apparatus over said overflow junction line, other common control apparatus operated responsive to said controlling digits from said overflow junction line for controlling said auxiliary selectors to select an idle one of said second choice junction lines, and means in said selector common control apparatus for rendering the numerical digits directly effective from said first selector to the desired exchange without registration at said control apparatus, said selector common control apparatus receiving and registering a predetermined number of numerical digits in case no idle first choice junction line is found by said first selector and in case an overflow junction line is utilized the controlling digits and the enregistered numerical digits are transferred from said selector common control apparatus to said auxiliary common control apparatus.
15. In a multi-office telephone system, a main exchange, a plurality of other exchanges, groups of junction lines connecting each exchange with said main exchange, first selectors in said main
- exchange having access to a first choice of said groups of junction lines, groups of common overflow junction lines accessible to said first selectors, auxiliary selectors in said main exchange connected to said overflow junction lines, groups of second choice junction lines accessible to said auxiliary selectors, common control apparatus for operating said first selectors to select an idle first choice junction line, other common control apparatus for operating said auxiliary selectors to select an idle second choice junction line, said selector common control apparatus operated in case no idle first choice junctions are found to receive and register the numerical digits and in case an idle overflow junction line is used transfer the enregistered digits designating the exchange together with the enregistered numerical digits to said auxiliary common control apparatus, said auxiliary common control apparatus receiving and registering the whole of said numerical digits.
16. In a multi-office telephone system, a main exchange, a plurality of other exchanges, groups of junction lines connecting each exchange with said main exchange, first selectors in said main exchange having access to a first choice of said groups of junction lines, groups of common overflow junction lines accessible to said first selectors, auxiliary selectors in said main exchange connected to said overflow junction lines, groups of second choice junction lines accessible to said auxiliary selectors, common control apparatus for operating said first selectors to select an idle first choice junction line, other common control apparatus for operating said auxiliary selectors to select an idle second choice junction line, said selector common control apparatus operated in case no idle first choice junctions are found to receive and register the numerical digits and in case an idle overflow junction line is used transfer the enregistered digits designating the exchange together with the enregistered numerical digits to said auxiliary common control apparatus, said auxiliary common control apparatus operated to simultaneously receive from the selector common control apparatus all of the enregistered digits and directly from the calling subscriber's dial the remaining unregistered numerical digits of the called number.
